UNITED STATES PATENT OFFICE.

EDWIN T. GREENFIELD, OF MONTICELLO, NEW YORK.

JUNCTION-BOX FOR ELECTRICAL CONDUCTORS.

No. 807,263.

Specification of Letters Patent.

Patented Dec. 12, 1905.

Application filed June 21, 1904. Serial No. 213,491.

To all whom it may concern:

Be it known that I, EDWIN T. GREENFIELD, a citizen of the United States, residing at Monticello, county of Sullivan, and State of New York, have made a new and useful Invention in Junction-Boxes for Electrical Conductors, of which the following is a specification.

My invention is directed particularly to improvements in junction-boxes like those disclosed in my prior United States Patents No. 642,521, granted January 30, 1900; No. 651,484, granted June 12, 1900, and No. 665,677, granted January 8, 1901; and it has 10 for its objects, first, to provide means for effectually closing such of the inlet-openings as are not needed when the box is put in place; second, to provide means whereby the inleading ends of the armored conductors or 15 conduits may be effectually clamped or held in place within the inner surface of the box, the arrangement being such that the same means which is utilized to effect the closure of such of the inlet-openings as are not in use 20 is also utilized to effect the clamping action 25 upon the inleading ends of the armored conductors or conduits.

For a full and clear understanding of my invention such as will enable others skilled 30 in the art to construct and use the same reference is had to the accompanying drawings, in which—

Figure 1 is a plan view of a junction-box with my improvement applied thereto, illustrating also two inleading flexible armored conductors secured thereto. Fig. 2 is a sectional view taken through Fig. 1 on the line A B and as seen looking thereat from the left toward the right in the direction of the arrows, the armored conductors being shown in side elevational view in dotted lines. Fig. 3 is a sectional view taken through Fig. 1 on the line C D and as seen looking thereat from the bottom toward the top of the drawings in 40 the direction of the arrows, the armored conductors being shown in end elevational view. Fig. 4 is a detail side elevational view of one of the shutters or disks which close the unused inlets, and Fig. 5 is a perspective view 45 of the means for holding the shutters or closing means and also for clamping the ends of

the inleading armored conductors or conduits.

Referring now to the drawings in detail, in all of which like numerals of reference represent like parts wherever used, 1 represents a junction-box of well-known form, provided with a series of inlets 2 2 2 for receiving the incoming ends of armored conductors or conduits 3, 4 4 being ears or lugs provided with screw-holes for securing the lid or cover of the box, (not shown,) said box being provided with the usual screw-holes in its bottom for securing it by screws directly to the ceiling or side wall.

5 is a clamping-ring the exterior diameter of which is such as to adapt it to fit snugly within the inner concentric surface or wall of the box, said ring being provided with downwardly-extending locking lugs or ears 9 9 9, 60 of interior curvilinear form, on their under surfaces, as shown at 11 11, and having interior grooves 10 10, adapted to receive shutters or disks 12, of curvilinear form, at their upper ends, the arrangement being such that 65 when these disks are in position and the clamping-ring secured within the box each of said disks will close a corresponding inlet-opening 2.

6 6 are screw-holes passing through ears or lugs on the interior of the clamping-ring 5 and adapted to receive screws 8 8, the screw-threaded ends of which may be secured in integral lugs or ears 7 7 in the bottom of the box.

85 In using the box it is first secured in place upon the ceiling or against the wall by screws passing through the bottom, as shown in Fig. 1, and such of the shutters or disks 12 are removed by withdrawing them from the grooves 9 9 10 10 of the clamping-ring 5 as may be necessary to accommodate the desired number of inleading armored conductors or conduits 3 3, two being shown in the drawings. These conductors or conduits are inserted as shown 9 9 in Figs. 1 and 2, and the clamping-ring inserted within the box so that the downwardly-extending locking-lugs 9, with their curvilinear interior surfaces 11, will rest snugly upon the armor of the conductors or conduits, the shutters or disks 12 remaining in corresponding downwardly-extending

closing the corresponding inlets, as clearly shown. The screws 8 8 are then inserted and secured as shown in Figs. 1, 2, and 3 and in such manner that all of the parts are firmly 5 secured together and the inner ends of the armored conductors or conduits locked against any possible movement.

This form of junction-box possesses an especial merit in that the shutters or disks 12 10 fit snugly within the grooves 10 and are not readily lost in transportation, so that, in effect, the clamping-ring 5 and shutters 12 12, which perform the double function of clamping 15 the inleading ends of the armored conductors and closing the unused openings, are for all practical purposes a single piece. Such a structural arrangement avoids or overcomes the objectionable feature of breakage in the putting of the box in position, as often 20 occurs with that form of junction-box disclosed in my prior patent, No. 642,521, in which the closing-disks are integral with the box, such breakage occurring by reason either of imperfect casting or careless manipulation 25 in breaking down or out the closing-disks to the inlets. It also avoids the necessity of providing a separate set-screw or clamping device for each inleading armored conductor or conduit and simplifies the construction 30 of the conduit-box itself in that it avoids the necessity of providing necks for supporting such set-screws.

I do not limit my invention to the especial 35 details of construction disclosed in the accompanying drawings, as the same might be departed from and still come within the scope of my claims hereinafter made. Nor do I limit the structural arrangement to a circular form of box, as obviously the same might be rectangular or of any preferred shape, the clamping means 5 being of corresponding 40 concentric conformation and adapted to rest upon the inleading ends of all of the armored conductors or conduits and to firmly clamp or hold the same from withdrawal therefrom.

I am aware that a two-part junction-box 45 has heretofore been devised in which there are cut in the side walls of each part of the box semicircular openings provided with concentric semicircular grooves for receiving circular disks in such manner as to close such of the openings as it is not designed to use in connection with house-conduits, the same being held together by screws passing through 50 the lid or upper portion of the box and into the side walls of the lower portion thereof, but without any binding action whatever upon the ends of the conduits or cables. My invention differs from this in that I provide 55 independent of the box for performing the double function of holding the detach-

able disks and simultaneously gripping or holding such of the ends of the conduits or cables as may be joined to the box.

Having thus described my invention, what 65 I claim, and desire to secure by Letters Patent of the United States, is—

1. A junction-box provided with clamping means concentric with the inner surface or wall of the box and additional means for 70 causing the same to act simultaneously upon all of the ends of the inleading armored conductors or conduits.

2. A junction-box provided with a series of inlets; a series of shutters or disks one for 75 each inlet, and clamping means concentric with the inner surface or wall of the box for holding the shutters or disks in such position as to close the inlets.

3. A junction-box provided with a series of 80 inlets and a series of shutters or disks for closing said inlets, said shutters or disks being supported by a ring concentric with the inner surface or wall of the box and detachable therefrom.

4. A junction-box provided with a series of inlets; in combination with a clamping-ring concentric with the inner surface or wall of said box and a series of shutters or disks carried by said clamping-ring; together with 90 means for securing the clamping-ring to the bottom of the box and in such position as to hold the inleading ends of corresponding armored conductors and to maintain the shutters or disks in such position as to close 95 the unused inlets.

5. A junction-box provided with a clamping-ring having curvilinear lugs adapted to fit about the ends of inleading armored conductors, and means for securing detachable 100 shutters or disks opposite the unused inlets; together with means for securing said ring to the bottom of the box.

6. A junction-box provided with a plurality 105 of inlets for the reception of the ends of inleading conductors or conduits; in combination with removable shutters for closing the same; together with means common to all the inlets for clamping the shutters and conduit or cable ends in position, and additional means for securing the aforesaid means to the bottom of the box.

7. A junction-box having the side walls provided with openings for the reception of the ends of inleading conductors or conduits; 115 in combination with removable shutters for closing the same and removable clamping means adjacent to said inlets for clamping the shutters and conduit or cable ends in position, said clamping means being secured to 120 the bottom of the box.

8. A junction-box having circular open-

ags in the side walls of the box proper; in combination with removable shutters and means within the box for securing the shutters in front of the openings, the shutters, 5 when in position, resting upon the bottom of the box.

9. A junction-box having circular openings in its side walls and a series of detachable shutters for closing the same; in combination with means located wholly within the box for securing the shutters in place, said

means being adapted also to grip or hold the ends of inleading conduits or cables in such of the openings as are not provided with shutters.

In testimony whereof I have signed my name to this specification in the presence of two subscribing witnesses.

EDWIN T. GREENFIELD.
